UNITED STATES PATENT OFFICE.

LEO D. PANGBORN, OF EAU CLAIRE, WISCONSIN.

DESIGN FOR A DOLL OR BABY CARRIAGE BODY.

53,523.

Specification for Design.

Patented July 8, 1919.

Application filed March 5, 1919. Serial No. 280,864. Term of patent 7 years.

To all whom it may concern:

Be it known that I, LEO D. PANGBORN, a citizen of the United States of America, residing at Eau Claire, Eau Claire county, and State of Wisconsin, have invented a new, original, and ornamental Design for a Doll or Baby Carriage Body, of which the following is a specification, reference being had to the accompanying drawing, forming part hereof, in which—

Figure 1 represents a perspective view showing one side of a doll or baby carriage

body embodying my new design, and Fig. 2 is a similar view showing the opposite side.

I claim:—

The ornamental design for a doll or baby carriage body, as shown.

Signed at New York city, New York this 24 day of February, 1919.

LEO D. PANGBORN.
